SUPPLY PUMP FOR ENGINES

Max Hurst, Stuttgart, Germany, assignor to
 Robert Bosch Aktiengesellschaft, Stuttgart,
 Germany

Application October 17, 1934, Serial No. 748,651
 In France October 20, 1933

4 Claims. (CL. 103—207)

This invention has for its object to provide a supply pump for heavy oil engines operable by a shaft of the engine and also by a manually actuated mechanism.

- 5 The invention has in view the provision of a manual control of which all of the members are easily accessible from the exterior and which does not interfere in any way with the tightness of the pump housing.
- 10 10 It concerns a supply pump for heavy oil engines and other applications operated by a shaft of the engine and by a manually operated mechanism, characterized by the fact that the manual mechanism is exteriorly mounted upon the pump housing and actuates a reciprocating member from the side thereof which is inaccessible from the exterior whereby this mechanism is controlled from without through a hand lever mounted on an accessible side of the pump housing.
- 15 15 The following detailed description discloses one form of the mechanism in which the manual means consists of a slide mounted in an outer portion of the pump housing and actuates from the exterior the reciprocating elements of the pump.
- 20 20 Fig. 1 is a longitudinal sectional view of the supply pump and a part of the body of the injection pump and its cam shaft; and
- 25 25 Fig. 2 is a vertical sectional view taken on line 2—2 of Fig. 1.

The supply pump is mounted on the injection pump of known type consisting, for example, of four individual pumps, the pistons 2 of which are actuated through the intermediary of tappet rollers 4, tappets 5 and cams 18 from shaft 3 mounted in the housing of the injection pump.

The supply pump 8 draws oil from the principal supply tank by way of passage 9. The body of the pump 10 which forms the supply pump carries a tubular projection 11 extending into the interior of the injection pump. Within the tubular member 11 is guided a tappet 12 which actuates the piston 15 of the supply pump through the intermediary of a spring 13 and stem 14. The piston 15 reciprocates in the body of pump 10 and compresses a return spring 16. An end cap 24 closes the pump body 10. An intake valve 19 and a discharge valve 20 are mounted in the pump body 10. A cam shaft 3 having cam 18 actuates the supply pump 8. The tappet 12 is reciprocative in the interior of the pump 10 and functions against the resistance of springs 13 and 16. This movement is transmitted to the piston 15 by the tappet stem 14. The combustible which is transferred through the interior of the pump

to the face of the piston opposing the tappet stem 14 between the intake valve 19 and the discharge valve 20 is discharged past the discharge valve 20, the intake valve being closed.

In accordance with the present invention the supply pump is provided with a mechanism adapted for the manual actuating thereof. This mechanism for manual actuation comprises a slide rod 25 mounted in an outer position of the casing 10 of the supply pump. This slide rod 10 10 10 is formed of a slide portion 25₁ and a guide stem 25₂ of lesser diameter. A return spring 28 engages at one end with a shoulder 35 of the portion 25₁ of the slide rod and at the other end with an opposing shoulder 29 of the guide bore 30. 15

The slide rod 25 is controlled by a hand lever mounted on the accessible side of the body 10 of the pump.

The hand lever 26 is positioned in a plane passing through the axis of the pump piston 15, and is 20 oscillatory on a pivot 31 mounted in a yoke 32 placed on an extension of the cap 24 of the pump cylinder 10. The yoke extension 32 for hand lever 26 is detachably held by retainer 34 in a recess in the outer end of cap 24. A link 33 connects the arm 26₁ of the lever 26 to the end of the guide stem 25₂ of slide rod 25. 25

Slide rod 25 carries at its end a finger 27 adapted to engage the tappet 12 which is so disposed on the side of the pump which is inaccessible from the exterior.

The operation of the hand pump is as follows: The arm 26₂ of the lever 26 is moved in the direction of the arrow f₁. This compresses the spring 28, the rod 25 sliding in the direction of arrow f₂. 35 The finger 27 engages the tappet 12 which actuates the piston 15 to discharge oil from the pump. On discontinuing pressure on arm 26₂ of lever 26 the spring 28 returns the slide 25 to its normal position. The finger 27 no longer engages the 40 tappet 12. The same is returned by the spring 13 and piston 15 is returned to its position by spring 16 thereby drawing oil into the pump chamber.

It will be seen that the objects of the invention 45 are thus attained in that a system is provided in which manual actuation of a supply pump is easily accessible from a point exterior thereof. No element of the manual actuation penetrates or traverses the chamber 10 of the supply pump, 50 and the fluid tightness of this is in no way diminished.

What is claimed is:

1. A supply pump of the type adapted to be driven by an engine or actuated manually, com- 55

prising a pump housing having a bore forming a pump cylinder, an end cap for said cylinder, a plunger reciprocative in said cylinder, a shaft adjacent one end of said housing for actuating said plunger from the engine, a hand lever mounted upon said end cap in a plane passing through the axis of said plunger, and a slide member operable by said hand lever to actuate said reciprocative plunger from a point adjacent said shaft, whereby normally inaccessible elements are actuated from the accessible end of said housing.

2. A supply pump of the type adapted to be driven by an engine or actuated manually, comprising a pump housing having a bore forming a pump cylinder, an end cap for said cylinder, a plunger reciprocative in said cylinder, a shaft adjacent one end of said housing for actuating said plunger from the engine, a supporting member retained in a recess in said end cap, a hand lever pivoted on said supporting member in a plane passing through the axis of said plunger, and a slide member operable by said hand lever to actuate said reciprocative plunger from a point adjacent said shaft, whereby normally inaccessible elements are actuated from the accessible end of the pump housing.

3. In a fuel supply means for internal combustion engines, an injection pump including a hous-

ing, pistons in said housing, a cam shaft within said housing having cams for actuating said pistons, a supply pump for said injection pump including a housing attached to a side wall of said injection pump housing, a plunger in said supply pump housing having a portion projecting into said injection pump housing and actuated by one of said cams, a slide member extending into said injection pump housing and contacting said projecting portion at a point adjacent said cam, and manually operable means mounted exteriorly of said housings for reciprocating said slide member.

4. In a fuel supply means for internal combustion engines, an injection pump including a housing, pistons in said housing, a cam shaft within said housing having cams for actuating said pistons, a supply pump for said injection pump including a housing attached to a side wall of said injection pump housing and having a portion projecting through an opening therein, a plunger in said supply pump housing having a tappet guided in said projecting portion and actuated by one of said cams, a slide member extending into said injection pump housing and having a finger contacting said tappet, and manually operable means for actuating said slide member from the exterior of said housings.

MAX HURST.
